*Primary Examiner—A. Hugo Word**Assistant Examiner—Doris Clark**Attorney, Agent, or Firm—Wolf, Greenfield & Sacks*[57] **CLAIM**

The ornamental design for a ladder step, as shown and described.

DESCRIPTION

FIG. 1 is a top view of a ladder step showing my new design;

FIG. 2 is a front view of said ladder step shown in FIG. 1;

FIG. 3 is a bottom view of said ladder step shown in FIG. 1;

FIG. 4 is a back view of said ladder step shown in FIG. 1;

FIG. 5 is a side view of said ladder step, the broken lines showing additional ladder steps are for illustrative purposes only and form no part of the claimed design.

FIG. 6 is a top view of said ladder step of FIG. 1, in the form of a blank, prior to bending into the form of FIG. 1;

FIG. 7 is a front view of said ladder step in blank form shown in FIG. 6;

FIG. 8 is a back view of said ladder step in blank form shown in FIG. 6;

FIG. 9 is a side view of said ladder step in blank form shown in FIG. 6; and,

FIG. 10 is a perspective view of said ladder step of FIG. 1, the broken lines showing a ladder are for illustrative purposes only and form no part of the claimed design.
